UNITED STATES PATENT OFFICE.

OTIS D. THOMPSON AND HOWARD F. SMITH, OF ELKHART, INDIANA.

SWEEPER.

SPECIFICATION forming part of Letters Patent No. 447,381, dated March 3, 1891.

Application filed May 21, 1890. Serial No. 352,599. (No model.)

To all whom it may concern:

Be it known that we, OTIS D. THOMPSON and HOWARD F. SMITH, citizens of the United States, residing at Elkhart, in the county of 5 Elkhart and State of Indiana, have invented certain new and useful Improvements in Sweepers; and we do hereby declare the following to be a full, clear, and exact description of the invention, such as will enable 10 others skilled in the art to which it appertains to make and use the same.

This invention relates to sweepers for lawns, roads, &c., and is an improvement on that patented to Otis D. Thompson, April 29, 1890, 15 and numbered 426,882.

The object of the present invention is to improve the operation of the machine and to provide means whereby it is adapted to follow the surface inequalities of the ground over 20 which it passes, and also to provide means whereby the sweepings are carried to the rear end of a box, basket, or other suitable receptacle to prevent the banking up of the sweepings at the mouth of said receptacle and pre- 25 clude its filling.

To these ends the invention consists in certain features derived from the former invention in combination with certain new and novel features of construction, all of which 30 will fully appear from the following description and claims, taken in connection with the accompanying drawings, in which—

Figure 1 shows in perspective view a sweeper made according to our present invention; 35 Fig. 2, a central longitudinal vertical section of the same; Fig. 3, a view of a portion of the sweeper, showing the means for adjusting the height of the brushes with relation to the ground; Fig. 4, a detail in perspective of 40 the "sweepings-receptacle" and top casing; Fig. 5, a detail in perspective of the shoe for guiding or deflecting the sweepings into the receptacle; Fig. 6, a detail in perspective of the brushes.

Similar letters in all the views indicate 45 similar parts.

A indicates the drive-wheel, which is formed with the peripheral rack *a*, adapted to engage a pinion mounted upon the journal *b* of the 50 brush *B*, said brush being supported in bearings on a bracket *C*. This bracket is formed of a bar having its ends bent at right angles

to form arms *c c*, the ends of said arms serving as the bearings for the journal of the brush. The bracket is pivotally connected at 55 *c'* to the spindles of the drive and companion wheels, which allows of that portion carrying the brush to rise and fall, this movement being limited by the length of the slot *d* in the side piece *D*, through which one end of the 60 journal *b* passes.

F is a spring, connected at one end to the side piece *D*, and its other free end bears upon the journal bearing on frame or bracket *C*, and forces the said bracket to the bottom 65 of the curved slot. When a strong resistance—such, for instance, as rough ground or heavy grass may give—is met, the upward pressure will force the brush and its spring up until the resistance is passed, when the 70 brush will instantly assume its former or normal position.

The side pieces or frames *D D* are connected at their outer ends by rod *k*, and are made with the circular portions *d' d'*, which act as 75 faces for the inner sides of the drive-wheel *A* and the companion wheel *G*. The circular portion for the wheel *A* also serves as a dust guard or screen to protect the gearing, while the portion *d'*, having no such function with 80 relation to the wheel *G*, is partly cut away to reduce weight. The side pieces *D D* are provided with the extensions *d''*, which are recessed, as at *d''*, and provided with pins or lugs 85 *d''*, to which are pivotally secured the lower ends of handle *H*. The outer ends of the extensions *d''* serve as bearing-points for the journal *i* of the roller *I*.

J is a shoe formed with the knife-edge *j* and the side flanges *j'*. This shoe is hung from 90 the rod *k* by curved arms *l*, passing under the journal *b*, and which arms are provided, respectively, with the eyes *l' l''* at each end, the eyes *l'* encircling the rod *k*, and the eyes *l''* being connected to the lower part of the flanges 95 *j'* by bolts or other suitable connections. The upper edge of the shoe rests on and is supported by the hopper portion *n* of a sheet-iron or other casing *N*, which opens into a receptacle *M*, said receptacle being composed of 100 wood, wire-netting, or other suitable material, and formed of the floor *m* and cover *m'*. The receptacle is connected to the casing *N* by hooks and pins *m''*, or other suitable connec-

tions. Upon releasing the hooks the receptacle may be removed and the contained grass or other sweepings emptied.

By reason of the connections of the shoe 5 with the frame, it will be readily seen that the shoe is permitted to rise and fall to adapt itself to the inequalities of the ground over which the machine passes.

The casing N is formed with the mouth or 10 hopper n and the inclined and curved portions n' n², the portion n² being hinged, as shown at n³, and adapted to be sprung over a portion of the periphery of the circular parts d' d² of the side frames. It will now be seen that 15 by reason of the casing N and side pieces D D' a chamber is formed, which admits air from beneath and allows it to pass through the hopper into the receptacle. The rapid revolution of the brush creates a strong current 20 of air, which carries the sweepings to the rear of the receptacle, and thus enables the receptacle to be entirely filled and prevents the banking up at the mouth of the hopper.

It will be seen that the manner of connecting 25 the brush by means of the arms c to the spindles of the drive and companion wheels not only allows of the substantially vertical adjustment of the brush with relation to the ground, but also preserves the gearing connection of the rack and pinion in all the positions 30 of the adjustment.

We have shown and described our inven-

tion as applicable to that class of sweepers designed to be used for lawns and for light work generally; but it is evident that the 35 same principle can be applied to a larger and heavier class of machines adapted for sweeping roads, &c.

We claim—

1. In a machine of the class described, the 40 combination, with the spindles of the driving and companion wheels, of a revoluble brush connected by gearing with the driving-wheel and having a central spindle, arms connecting the spindles of the wheels and brush, and 45 springs adapted to bear on these arms and keep the brush in contact with the ground, as set forth.

2. In a machine of the class described, the 50 combination, with the spindles of the driving and companion wheels, of the revoluble brush connected by gearing with the driving-wheel and having a central spindle, arms connecting the spindles of the wheels and brush, springs adapted to bear on these arms, and a shoe 55 connected by arms to the frame, all substantially as and for the purposes set forth.

In testimony whereof we affix our signatures in presence of two witnesses.

OTIS D. THOMPSON.
HOWARD F. SMITH.
